UNITED STATES PATENT OFFICE.

THOMAS BLACKWOOD MURRAY, OF SCOTSTOUN, SCOTLAND.

INDUCTION-PASSAGES OF INTERNAL-COMBUSTION ENGINES.

1,318,224.

Specification of Letters Patent.

Patented Oct. 7, 1919.

Application filed October 31, 1918. Serial No. 260,528.

To all whom it may concern:

Be it known that I, THOMAS BLACKWOOD MURRAY, a subject of the King of Great Britain and Ireland, and a resident of 5 Scotstoun, in the county of Renfrew, Scotland, have invented certain new and useful Improvements in the Induction-Passages of Internal-Combustion Engines, and of which the following is the specification.

10 The invention relates to combustion engines having detachable cylinder heads, the cylinders being cast *en bloc* or in *en bloc* groups, and has for its object to provide an improved inlet manifold arrangement cast 15 integrally with the cylinder casting, and with the head of simple form and very adequately jacketed throughout.

According to the invention the inlet manifold of open-topped channel or other easily 20 molded shape is formed along the top of the cylinder casting adjacent to the cylinders substantially in a straight line and upon that side of the cylinders on which the inlet valves are. It is closed by the under side 25 of the detachable head with which joint is made.

From this channel, simple passages debouch through the detachable head to each 30 inlet valve. A passage (or passages) is also formed to the carbureter; this may either pass upward through the detachable head more or less downward through the cylinder body, or more or less horizontally there- 35 through to the side of the engine remote from the valves. This passage may be at the end of an *en bloc* group, or there may be a passage at each end, or when the engine is of four cylinders *en bloc*, it may be at the center of the block.

40 Alternatively, a passage or passages may extend to a carbureter located at the same side of the engine as the valves.

An illustrative example of the carrying out of the invention is shown in two accompanying sheets of explanatory drawings in 45 which Figure 1, Sheet 1, is to the left hand side a plan and to the right hand side an inverted plan, and Fig. 2 a sectional end elevation of a four-cylinder engine made according to the invention. 50

In this example the inlet manifold A of open-topped channel section is formed along the top of the cylinder casting B and is closed by the under side of the detachable head C. It lies on the side where are the 55 inlet valves D, is closely adjacent to them and communicates with them by passages E formed in the head. The channel like passage A communicates with the carbureter F by a transverse passage G formed in the 60 cylinder casting.

What I claim is:—

1. In a multi-cylinder combustion engine having a detachable head, inlet valves carried thereby, an inlet manifold in the form 65 of an open-topped channel formed in the cylinder casting and closed by the under side of the head casting adjacent to the cylinders, substantially in a straight line and to that side of them on which the inlet 70 valves are, passages in the head forming communication between the channel like manifold and the inlet valves and means for supplying carbureted mixture to said manifold. 75

2. In the inlet-manifold arrangement forming the subject-matter of the foregoing claim hereof, a channel-like passage means formed in the cylinder casting and closed by the head for admitting carbureted 80 mixture to the manifold.

In testimony whereof I have signed my name to this specification.

THOMAS BLACKWOOD MURRAY.
